CLAIM

The ornamental design for a bracket for a mounting assembly for a weight rack, as shown and described.

DESCRIPTION

FIG. 1 is a top, front, right perspective view of a bracket for a mounting assembly for a weight rack showing our new design;

FIG. 2 is a front view thereof;

FIG. 3 is a rear view thereof;

FIG. 4 is a left view thereof;

FIG. 5 is a right side view thereof;

FIG. 6 is a top view thereof; and,

FIG. 7 is a bottom view thereof.

The dot dash lines immediately adjacent to the shaded area define the bounds of the claimed design and form no part thereof. The broken lines depicting the remainder of the bracket for a mounting assembly for a weight rack show features that form no part of the claimed design.
